Primary Examiner—Holly H Baynham*Assistant Examiner*—Cynthia M Chin(74) *Attorney, Agent, or Firm*—Volpe and Koenig, P.C.(57) **CLAIM**

The ornamental design for a paintball field marker, as shown and described.

DESCRIPTION

FIG. 1 is a left side perspective view of a design for an paintball field marker according to the present invention;

FIG. 2 is a right side perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view thereof.

The details shown in broken lines are for illustrative purposes only and form no part of the claimed design.

1 Claim, 8 Drawing Sheets
